UNITED STATES PATENT OFFICE

JAMES F. MULHOLLAND, OF COLUMBUS, OHIO

BALLOON TOY

Application filed March 28, 1928. Serial No. 265,514.

My present invention relates to an improved balloon toy designed especially for use in the simulation of figures, more or less grotesque, resembling human beings. The primary object of the invention is the provision of means, and of a process for carrying out the invention whereby a main balloon or inflated elastic body may be used to simulate the body and head portions of a human being, and especially contemplates the attachment of portions simulating limbs to the body portion. Thus in carrying out my invention, I use for example one large balloon which is inflated with air or gas in usual manner and fashioned to simulate the body and head portion of a human being, and two smaller balloons are inflated and then attached to the body portion of the main balloon to simulate arms. The toy is provided with a base upon which it is adapted to rock or oscillate, and the arms or limbs are attached to the body portion in such manner that they are free to swing with relation to the body. The invention consists in certain features of construction and combinations and arrangements of parts as will hereinafter be more fully set forth and claimed.

In the accompanying drawings, I have illustrated one complete example of the physical embodiment of my invention wherein the parts are combined and arranged according to the best mode I have so far devised for the practical application of the principles of my invention.

Figure 1 is a view in elevation showing the toy of my invention and indicating by dotted lines the oscillating movement of the body and of the limbs;

Fig. 2 is a plan view of the supporting base for the toy;

Fig. 3 is an enlarged detail sectional view showing the manner of attaching the main body balloon to the base;

Fig. 4 is a view showing one of the small balloons and indicating the arrangement of a cement patch by which the small balloon is joined to the larger one, the parts being separated; and

Fig. 5 is an enlarged detail sectional view

showing the joint between the body portion and one of the arms.

In carrying out my invention, I use a rubber balloon which of course is elastic and adapted to be inflated, the mouthpiece 2 being used to blow air into the balloon for expanding it to the general shape indicated in Fig. 1. After the balloon has been inflated, a knot 3 is tied in the mouthpiece to prevent escape of air.

The balloon as thus inflated is fashioned to form or approximately simulate the human body by the use of a neck string 4 which is tied in a knot or bow 5 about the balloon to form a constriction, and the upper part of the balloon thus becomes the head portion 6 of the human body which is simulated. The inflated balloon is supported upon a base block 7 which is notched as at 8 for the purpose of simulating a pair of feet or a pair of shoes, and at the rear the baseboard is notched or slotted at 9.

Between the two notches 8 and 9, a hole or opening 10 is provided in the baseboard and it will be apparent that the knotted mouthpiece is passed through the opening 10 from above and then clinched within the notch 9 at the rear for the purpose of anchoring the balloon and also to prevent its deflation. The balloon as thus supported may have almost a universal movement or oscillation with relation to the baseboard as indicated by the dotted arrows at the top of Fig. 1.

The body portion of the balloon is provided with limbs, or members simulating limbs, as for instance the arms 11 and 12, but it will be understood that other limbs or projecting members may be used in connection with the body portion 1 or with the head portion 6. The two arms 11 and 12 are fashioned from smaller balloons by inflating the balloons through the mouthpieces 13 and tying the knots 14 therein to prevent deflation. These smaller balloons are attached at approximately the shoulder portions of the body 1 and become integral parts of the body as indicated in the sectional view of Fig. 5. For attaching the arms to the body, I use a solvent for the rubber which may be a liquid cement and a patch or drop
